UNITED STATES PATENT OFFICE.

CHARLES EMILE RIBARDIÈRE, OF PARIS, FRANCE.

HAIR CLIP.

Application filed February 19, 1926. Serial No. 89,280.

The present invention relates to improvements in hair clips and more particularly to such clips adapted for permitting a woman to removably and invisibly support 5 and secure ornaments or different masses of false hair such as coils, "chignons," pads, wigs, fringes or the like upon her short-cut hair.

The primary object of the invention is to 10 provide a hair clip of the class referred to having a very light, simple, compact and reduced structure composed of a minimum number of parts and adapted for being readily attached by the user or the hair dresser 15 to any desired portion of the hair and readily detached therefrom whilst being firmly retainable in the hair.

A further object of the invention is to 20 provide such a hair clip adapted for being entirely inconspicuous while performing its function of maintaining ornaments or false hair upon the mass of short-cut real hair.

A still further object of the invention is to provide such a hair clip adapted for 25 not injuring i. e. not crumpling or not breaking the real hair when attached thereto with its dependent mass of false hair or detached therefrom whilst performing an invariable retention of said false hair in the 30 selected position during any period of time.

A still further object of the invention is to 35 provide a wearless hair clip of the class described adapted for being utilized any number of times, that is to say for playing its retaining function over and over again.

With these and such other objects in view as will incidentally appear in the following description and claims, the invention consists in the novel construction, combination and arrangement of parts that will now be described in detail with reference to the accompanying drawing forming a part of same.

45 In said drawing:—

Figure 1 is a top plan view of the improved hair clip, assuming its swinging clamp to be in locked position.

Figure 2 is a bottom plan view of the improved hair clip.

Figure 3 is a longitudinal fragmentary edge view somewhat diagrammatic and partly in section of the improved hair clip, 55 assuming its swinging clamp to be in its sprung out position.

Figure 4 is a transverse sectional view of the device taken on line 4—4 of Figure 1.

Like references designate like parts throughout the several views.

This improved hair clip is primarily constituted by two juxtaposed rectangular metal plates preferably very slightly curved: an upper plate 1 and a lower plate 2 (the terms "upper" and "lower" being merely for the purpose of illustration). The upper plate 1 preferably has rounded corners and is pierced adjacent the latter with round holes 3 through which may be passed the threads or wires securing the ornament or the mass of false hair (coil, "chignon", pad, wig, fringe or the like) which has to be removably attached upon the short-cut real hair. Said upper plate 1 is also formed with a marginal flange 4 which by being clinched over the peripheral edge of the lower plate 2 firmly holds the two plates together. It is moreover stamped to present a depression 5 adjacent its fore end and three parallel rounded ribs, 6, 6^a, 6^b extending over the greater part of its length. The lower plate 2 is also stamped to present two round depressions 7, two shallow rectangular depressions 8 in the neighborhood of its fore end, a central longitudinal rib 9 and two side longitudinal ribs 10 for purposes that will presently appear. Said lower plate 2 is moreover pierced adjacent its four corners with round holes 3 registering with the corresponding holes in the upper plate for the above-stated purpose and with a hole 11 positioned so as to substantially correspond with the rear end of the central rib 6 formed in the upper plate.

Adjacent its rear end, the upper plate 1 is formed on its sides with oppositely disposed bearings 12 wherein are pivotally mounted the two outwardly bent ends of the two legs of a swinging clamp 13 preferably formed by a slightly flexible wire of rounded section, said two legs being substantially parallel, connected by a cross-strip 14, provided over the greater part of their length with sleeves 15 made of rubber or another soft resilient material and united at their fore ends by an integral portion bent upon itself as shown in Fig. 3 to present the shape of a claw 13^a which is adapted to lock the clamp 13 in position as will now be described.

Within the rib 6 formed centrally in the

upper plate 1 is housed a coil spring 16 which abuts at its rear end against the extremity of said rib and at its fore end against the rounded rear end of a bolt 17 which presents the notched contour clearly shown in Fig. 3 and is terminated forwardly by a nose or hook 17^a projecting from said rib when in normal locking position and adapted to engage with the claw-like fore

10 end of the flexible clamp 13 to lock same down when in extended position and release same when it has been brought to its retracted position against the antagonism of its spring 16.

15 To temporarily retract the locking bolt 17 there is provided a trigger 18 of flat structure as represented in Fig. 2. This trigger has a round perforation delineated by a slight flange for the purpose of being piv-

20 otally mounted on a slight protuberance 19 formed by the one or the other of the depressions 7 in the lower plate 2. Furthermore said trigger has an integral lug 18^a which constantly engages a notch 17^b cut 25 in the bolt 17 and a triangular or otherwise shaped portion 18^b which constantly protrudes outside of the plates 1 and 2 through an interruption of the flange 4 whereby by pushing the said trigger inward its lug

30 18^a forces the bolt 17 rearwardly against the spring 16 and thus releases the claw which can thus spring up and assume the position illustrated in Fig. 3 and therefore permit the user to disengage the ornament or the

35 mass of false hair fastened to the clip from the mass of her real hair.

When it is desired to again lock the swinging clamp 13 in closed position, all that is necessary is to snap its fore claw 40 underneath the hook 17^a of the bolt 17, which, upon release of the trigger, has been pushed back to its normal locking position and thus again protrudes outside the central rib 6.

45 When thus in its locked position, the clamp 13 has its two slightly flexible legs provided with rubber or other soft resilient sleeves 15 as above described accommodated within the respective grooves formed between the central rib 6 and the side ribs 6^a, 6^b so that said legs do not materially project above said central rib except at their fore end. The claw formed at said latter end is held down by the hook 17^a of the bolt 55 17 so that the tip of said claw is located and protected in the depression 5 and does not project.

It will thus be appreciated that when in 60 locked position the entire clip has no projecting part liable to damage the real hair of the user. Furthermore as it is entirely hidden under the ornament or mass of false hair temporarily attached upon said real hair, it is altogether inconspicuous and not 65 liable to open itself whereby any accidental

loss of the hair attachment is precluded. Lastly, owing to the resilient sleeves 15 provided around the legs of the clamp 13, the real hair of the user does not run the risk of becoming crumpled, broken, torn off or otherwise damaged since the pressure exerted on it is cushioned by said sleeves which also protect it from a direct contact with the metal of the clip and from any eventual stain due to such metal.

Whilst a convenient embodiment of the invention has been described with reference to the accompanying drawing, it will be understood that numerous minor constructional details might be changed without departing from the spirit and scope of the invention as set forth in the subjoined claims.

What I claim and desire to secure by Letters Patent is:—

1. A hair clip for the purpose set forth comprising an upper ribbed and depressed plate and a lower ribbed and depressed plate substantially of equal size firmly held in juxtaposed relation and having registering holes for securing the hair attachment, a swinging clamp pivotally mounted in bearings formed on the upper plate, a locking bolt pushed by a spring housed in a rib of the upper plate and engaging said clamp and pivotal means located between said plates and partly projecting laterally therefrom for retracting the bolt and unlocking the clamp.

2. A hair clip for the purpose set forth comprising an upper rectangular plate having three ribs extending over the greater portion of its length and delineating two grooves, a lower rectangular plate substantially of equal size firmly held against the upper plate, both plates having registering corner holes for securing the hair attachment, a swinging clamp formed of a slightly flexible wire bent upon itself to form two substantially parallel legs forwardly united by an integral claw-like bent portion, opposite bearings formed on the upper plate wherein are pivotally housed the ends of the clamp legs, a locking bolt housed in the central rib and forwardly shaped as a hook, a spring also housed in the central rib and abutting at one end against the end of said rib and at its other end against said bolt and pivotal means located between said plates and partly projecting therefrom for temporarily retracting the bolt and thus unlocking the clamp.

3. A hair clip for the purpose set forth comprising an upper rectangular slightly curved plate having a central rib and two side ribs extending over the greater portion of its length and forwardly formed with a depression, a lower rectangular slightly curved plate substantially of equal size firmly held against the upper plate by a clinched flange on the latter, registering corner holes

- being provided in said plates for passing the securing means of the hair attachment, a longitudinal swinging clamp formed of a slightly flexible wire bent upon itself to 5 form two substantially parallel legs locating themselves in the respective grooves between the ribs and forwardly united by an integral claw-like portion, resilient sleeves around said legs, opposite bearings formed 10 on the upper plate for pivotally supporting the outwardly bent ends of said legs, a locking bolt housed in the central rib, said bolt having a notch intermediate its length and being forwardly terminated as a hook, a coil 15 spring also housed in said central rib and abutting by its respective ends against the ends of said central rib and said bolt and a perforated trigger pivotally mounted flatly between the plates on an axis formed by the inner protuberance corresponding to a depression of the lower plate, a portion of said flat trigger protruding outside and laterally of the plates and another portion of said trigger shaped as a lug engaging the notch 20 in the bolt for retracting same and thus releasing the clamp. 25

In testimony whereof I affix my signature.

CHARLES EMILE RIBARDIÈRE.
